CLAIM

The ornamental design for a set of seven chess pieces, as shown and described.

DESCRIPTION

The pieces are designed to be used in 3-player chess, played on hexagons.

FIG. 1 is a perspective view of the set of seven chess pieces, showing my new design;

FIG. 2 is a front view thereof;

FIG. 3 is a rear view thereof;

FIG. 4 is a right view thereof; and,

FIG. 5 is a left view thereof.

My design is characterized by hexagonal bases, sloping sides and individual top character ornamentation.
